UNITED STATES PATENT OFFICE

ELBERT J. HALL, OF BERKELEY, CALIFORNIA, ASSIGNOR TO AMERICAN CAR AND FOUNDRY SECURITIES CORPORATION, A CORPORATION OF DELAWARE

SELF-PROPELLED RAILWAY CAR

Application filed June 9, 1926. Serial No. 114,608.

This invention relates to self-propelled railway cars, and more particularly to a car wherein an internal combustion engine is employed to drive a generator for supplying current to electric motors which drive the car. The object of the invention is to arrange the power plant so that it will not take up space available for passengers and cargo, and also to provide for complete control of the power plant from a forward compartment where the motorman is stationed and to so arrange the controls that a number of cars may be coupled together in a train and all operated from one set of controls. In the present invention I preferably make use of two internal combustion engines mounted side by side beneath the frame of the car, one operating in a right-hand direction and the other in a left-hand direction, and each engine being directly connected to a generator.

Each generator operates a separate motor, there being two motors, each operatively connected with a different axle of the trucks. Thus, if one engine or generator fails, the other unit is not interfered with and will be capable of propelling the car.

The engines are controlled from the motorman's compartment forward of the car, by air-operated throttles and the usual starting mechanism. The air-operated throttles on a plurality of cars can be placed under the influence of one controller by air-hose connections between the cars.

One form which my invention may assume is exemplified in the following description and illustrated in the accompanying drawings, in which—

Fig. 1 shows a plan view in section of the body of the railway car;

Fig. 2 shows a side elevation of the trucks and frame with the power plant in position thereon;

Fig. 3 shows a plan view in section of the forward portion of the car body;

Fig. 4 shows a sectional view in elevation of a portion of the frame from which the power plant is suspended;

Fig. 5 shows a sectional view taken on the line V—V of Fig. 4;

Fig. 6 shows a sectional view taken on the line VI—VI of Fig. 4;

Fig. 7 shows a plan view of the forward part of the frame with power plant in position thereon and the controls leading to the motorman's compartment;

Fig. 8 shows a diagram of the air-control for the governors, with certain parts in section;

Fig. 9 shows a longitudinal sectional view of the coupling between the engine and generator;

Fig. 10 shows a view partly in section and partly in elevation, of the coupling taken on the line X—X of Fig. 9.

The car in its present form includes a frame 10 carried on suitable trucks 11. An electric motor 9 is operatively connected to each axle of the front trucks. The body of the car is divided into a passenger-carrying space 12, cargo space 13, and motorman's compartment 14. The power plant for generating electricity to supply the motors includes two internal combustion engines 15 arranged side by side beneath the frame of the car, and each having its crank-shaft directly connected with a generator 16. One of these engines operates in a right-hand direction and the other in a left-hand direction, so as to overcome any tendency to tilt the car.

The mounting for the engines and generator is best shown in Fig. 4, and comprises a rigid support at the rear and a pivotal support at the front. The rigid support includes a pair of angle plates 17 bolted to the generator housing and in turn bolted to a flanged plate 18 secured between cross-sills 19. To insulate the metallic plates from each other so as to reduce vibrations, I preferably arrange layers of felt 20 above and below the plate 18. The edges of the felt are turned up, so as to form a cushion in a horizontal direction as well as vertically. The front support consists of a yoke 21 pivoted at its lower ends to the front end of the engine housing and pivoted at its upper end to a second yoke 22, which in turn is bolted rigidly to a cross-sill 23. This allows some flexibility in a fore-and-aft direction.

In front of each engine is a radiator 24 sup-

100

ported upon the frame by brackets 25 near the top and at each side. The lower end of the radiator is braced by means of links 26 pivotally connected to the engine housing.

5 In practice a fan may be arranged behind each radiator and mounted directly on the front end of the crank-shaft 27. Also there is a compressor 28 fixed upon each engine at the front and inner side thereof, and driven 10 from the crank-shaft at half engine speed. These compressors supply air to tanks 29 for operating the brakes and for other purposes.

Each engine has its exhaust manifold 30 arranged at the outer side, and an exhaust 15 pipe 31 leads upwardly inside of the body of the car to a muffler 32 arranged on the roof of the car. Each engine is preferably fitted with an electric starting motor, not shown, which is suitably controlled from the motor- 20 man's compartment. Preferably there will be two throttles for each engine, one controlled by a governor and the other controlled by a diaphragm 33 which is actuated by air through pipes 34 connected with an air

25 supply line 34^a through a control valve 35, which valve is located in the motorman's compartment. The valve 35 controls the speed of both engines, and either engine may be cut off by means of valves 36 arranged in 30 the pipes 34. The supply line 34^a may receive its supply of air from the tank 29, and the admission of air to diaphragms 33 will be under control of the valve mechanism 35.

To enable a number of cars to be coupled 35 together so that the valve 35 on the front car will control the engines on all cars, I provide an air line 36^a on each car, which connects with the valve mechanism 35 and pipes 34, through a branch 36^b. The line 36^a has a 40 flexible coupling 36^c at each end for connection with a similar coupling on the adjacent car. These couplings may be of the type used in air brake systems, and when coupled together provide a continuous air line from 45 the front car to the rear, all under control of the valve mechanism 35 of the front car. Thus all diaphragms 33 on the various cars can be controlled by one operator. It therefore becomes possible to make up a train of 50 these cars for travel over a main line, and then break up the train into one or more cars to travel over various branch lines.

55 Preferably the intake manifolds of both engines are connected across by a pipe 37 to insure equalization of the combustible mixture admitted to the two engines, so that both engines will run at approximately the same speed. The valve 37^a is arranged in the pipe 37, being normally opened; but it is closed 60 when it is desired to operate one of the engines alone.

The coupling between the crank-shaft of each engine and the armature shaft of the generator is preferably in the form shown in 65 Figs. 9 and 10, wherein the drive wheel 38 is

bolted to a flange 39 formed on the end of the crank-shaft 27. The drive wheel is enclosed in a housing 40 which is bolted to the housing 16 of the generator as indicated at 41. The housing 40 has a lip or flange 41^a, to fit within the generator housing and sustain the weight of the rear end of the engines. This housing 40 has openings 42 at its top and bottom, and a fan or blower 43 is bolted to the drive wheel and so arranged as to draw air in through the generator and blow it out through the openings 42. Fixed to the armature shaft 44 is a flange 45 carrying a ring gear 46. This ring gear meshes throughout its periphery with an internal toothed gear 47 formed on the fan 43 and carried by the drive wheel 38, thereby forming a driving connection between the crank-shaft and the armature shaft. The end of the armature shaft extends into a bearing 48 formed in the drive wheel.

70 The foregoing coupling affords the desired amount of flexibility between the crank shafts and the armature shaft, and in addition provides means for cooling the generator.

75 The saving effected in cargo and passenger space by arranging the engines and generators as shown, is considerable. Each engine and generator set is from ten to fifteen feet in length, and since there are two units of this character on each car, it will be seen that if they were placed above the frame, a large engine room would have to be provided. Furthermore, by having the power plant located below the frame, the entire body, from one end to the other, will be unobstructed, and passageways or corridors can be provided, so that when a number of the cars are 80 coupled in a train, the passengers and attendants can pass from one car to the other.

85 In and by the present invention it becomes possible to operate and maintain a railway car with self-contained power plant in substantially the same manner as cars using a trolley system. The motorman need not be particularly skilled in the care and operation and repair of internal combustion engines. The controls are all remote, and no more complicated than the controls used on electric cars. The engines, being below the car, are not readily accessible, and it is not likely that inexperienced motormen will tamper with them. Should one engine or unit fail, the other is sufficient to drive the car to the nearest railway shop, where skilled repairmen are stationed, just as in railway practice.

90 100 105 110 115 120 125 130 The unit control for both engines of a car and the interconnecting pipe 37 between the intake manifolds of adjacent engines, will insure substantial uniformity in the speed of the engines and the current output of the generators. However, even if there should be some unevenness as between motors or generators, the fact that the two generators or motors are not interconnected electrically will insure freedom of trouble such as would be

encountered where a number of generators are in the same circuit and have to be balanced.

Various changes in the construction and arrangement of the several parts herein shown and described may be employed without departing from the spirit of my invention as disclosed in the appended claims.

Having thus described my invention, what I claim as new and desire to secure by Letters Patent is:

1. In a self-propelled railway car, a power plant, including a pair of internal combustion engines, one operating in a right-hand direction and the other in a left-hand direction, arranged side by side beneath the frame of the car, a generator directly connected to the crank-shaft of each engine, said engines and generators being suspended beneath the frame by means of a flexible connection at one end and a rigid connection at the other end.

2. In a self-propelled railway car, a frame, trucks for supporting the frame, a pair of internal combustion engines, each having a generator directly connected to its crank shaft, said engines and generators being suspended beneath the frame, and electric motors, each connected to one of the generators and mounted for driving different axles of the car trucks.

3. In a self-propelled railway car, a frame, a pair of internal combustion engines, each with a generator directly connected to its crank shaft, and flexible means for suspending said engines and generators beneath the frame.

4. In a self-propelled railway car, a frame, an internal combustion engine, a generator directly connected to the crank case of the engine and both the generator and the engine being arranged beneath the frame, and suspension means for said engine including a pivotal connection at one end and a rigid connection at the other, said pivotal connection permitting fore-and-aft movement.

5. In a self-propelled railway car, a frame, an internal combustion engine, a generator directly connected to the crank case of the engine and both the generator and the engine being arranged beneath the frame, and suspension means therefor comprising a pivotal connection at the front and a rigid connection at the rear, said rigid connection including insulating material to absorb vibrations and said pivotal connection permitting fore-and-aft movement.

6. In a self-propelled railway car, a frame, a body thereon, an internal combustion engine arranged beneath the frame of the car, a pipe connected with the exhaust manifold of the engine leading upwardly inside of the body of the car, and a muffler arranged on the roof of the car.

7. The combination of a plurality of self-propelled railway cars adapted to be coupled

together in a train, an internal combustion engine on each car, a generator driven by each engine, an electric motor for driving each car and receiving its current from the generator thereon, fluid pressure means for controlling the throttle of each engine, a control for the fluid pressure means on each car, and air line train couplings whereby the various fluid pressure controllers on the different cars may be actuated by a single fluid pressure control.

8. The combination of a plurality of self-propelled railway cars adapted to be coupled together in a train, an internal combustion engine on each car, an air-operated diaphragm controlling the throttle of each engine, a control valve on each car for controlling the air-operated diaphragm, and means whereby the air-operated diaphragms on all of the cars in the train may be placed under the influence of a single control valve.

9. In a self-propelled railway car, a power plant, including a pair of internal combustion engines arranged side by side beneath the frame of the car, a generator directly connected to the crank shaft of each engine, and means for suspending said engines and generators beneath the frame, comprising a flexible connection at one end and a rigid connection at the other end.

10. In a self-propelled railway car, a power plant including a pair of internal combustion engines arranged beneath the car, a valved connection between the engines, a generator having operative connection with the crank shaft of each engine, and electric motors, each operatively connected to one of the generators and mounted for driving different axles of the car trucks.

ELBERT J. HALL.
